UNITED STATES PATENT OFFICE.

PATRICK F. CHARLES AND JOHN J. BRODERICK, OF GIRARD, OHIO, ELIZABETH F. BRODERICK, ADMINISTRATRIX OF SAID JOHN J. BRODERICK, DECEASED, ASSIGNEES OF ONE-TENTH TO EDWARD A. KIRBY, OF GIRARD, OHIO, NINE-TWENTIETHS TO SAID PATRICK F. CHARLES, AND NINE-TWENTIETHS TO SAID ELIZABETH F. BRODERICK, INDIVIDUALLY.

MAKING WROUGHT-IRON.

1,204,939.

Specification of Letters Patent. Patented Nov. 14, 1916.

Application filed January 23, 1914. Serial No. 813,970.

To all whom it may concern:

Be it known that we, PATRICK F. CHARLES and JOHN J. BRODERICK, citizens of the United States, residing at Girard, in the county of Trumbull and State of Ohio, have invented new and useful Improvements in Making Wrought-Iron, of which the following is a specification.

This invention relates to improvements in puddling furnaces and processes for making wrought iron, one object of the invention being to provide a wrought iron making plant comprising a rotary boiling furnace, a puddling furnace and means for transferring metal from the boiling furnace to the puddling or balling furnace for manual puddling in the latter; another object being to provide a wrought iron making plant comprising a double balling furnace and a pair of revolving boiling furnaces arranged at opposite sides of the balling furnace, and means to transfer metal first from one boiling furnace and then from the other to the balling or puddling furnace and thus enable wrought iron to be readily produced in large quantities and by the employment of comparatively few workmen.

Another object of our invention is to provide an improved process for making wrought iron and by means of which the use of a revolving boiling furnace may be availed of in melting, fluxing, boiling, and graining pig iron, without the employment of manual labor, and a balling furnace then employed to which the said treated pig iron is transferred from the boiling furnace and in which balling furnace the operations of dropping, turning, breaking up and balling the metal may be manually performed by skilled puddlers, thus enabling pig iron to be initially treated without the employment of manual labor and then finished or balled manually thus greatly economizing in the employment of manual labor in the making of wrought iron and hence materially lessening the cost of production of such iron while greatly promoting the interests and reducing the labor of the puddlers.

In the accompanying drawings:—Figure 1 is a plan of a wrought iron making plant arranged in accordance with our invention and comprising a pair of boiling furnaces, a

double balling or puddling furnace, cranes for transferring the initially treated metal from the boiling furnaces to the balling or puddling furnace. Fig. 2 is a vertical longitudinal sectional view of one of the boiling furnaces in which the metal is initially treated. Fig. 3 is a vertical longitudinal sectional view of the balling or puddling furnace. Fig. 4 is a vertical transverse sectional view of the same. Fig. 5 is an elevation of the same.

Heretofore it has been proposed to produce wrought iron without the employment of manual labor in puddling and by the use of revolving furnaces in which the pig iron was melted and otherwise treated. Such process and the employment of such furnaces has been, however, practically unsuccessful, the metal produced thereby being of greatly inferior quality and not properly to be called serviceable wrought iron such as is demanded in the arts and purposes of commerce.

The practice of melting the metal in the same furnace in which it is to be balled or puddled has been resorted to and this is extremely expensive inasmuch as it requires the services of skilled puddlers who must perform exhausting as well as highly skilled manual labor at such furnaces during practically the entire process of converting pig iron into wrought iron.

We have discovered that in the making of wrought iron a revolving boiling furnace may be availed of, which does not require the services of puddlers, during the initial steps of converting pig iron into wrought iron and up to the point of graining the iron, and that the metal thus prepared may be thus transferred to a balling furnace and finished in such balling furnace by manual manipulation by puddlers, so that the employment of such skilled manual labor is rendered necessary only during the finishing portion of the process of making wrought iron.

We have also invented an improved process by which wrought iron may be thus made.

In accordance with our invention and in order to carry out our improved process we provide, as a wrought iron making plant, a

double balling furnace 1 and a pair of revolving boiling furnaces 2. The double balling furnace comprises a balling furnace 3, a fire chamber 4 at one side of and communicating with the balling furnace, a flue 5 leading from the opposite side of the balling chamber and a smoke stack 6 into the lower end of which the flue 5 discharges. At each end of the balling furnace is a vertically movable door 7 each door being provided with a swinging frame 8 and an operating chain 9 to enable the door to be pulled up when drawing the balls. Each door has the usual comparatively small opening or door bit 10 through which the baller or puddler performs his work. In one end wall of the fire chamber is a fire hole 11 through which coal is placed on the fire, in cases where the charge is fired with coal as a fuel. In the roof or top 12 of the balling furnace is an opening over which is a movable door 13 which may be moved from one side of said balling furnace to the other and over said door is a charging chute 14.

25 Each boiling furnace 2 comprises a cylindrical revoluble body 15, a fixed fire chamber 16 and a flue 17. The cylindrical chamber body 15 is lined with fire brick and is provided at the end next the fire chamber 16 with an opening 18 for the entrance of fuel gas and at the opposite end with an opening 19 for the exit of products of combustion the opening 19 being also the opening through which the pig iron is placed in the body of the furnace. A door 20 is also provided to afford access to the charging opening.

A supporting frame 21 is also provided, which is under the revoluble body of the furnace and is provided with anti-friction rollers 22 on which the lower side of the furnace body 15 rests and on which the said furnace body is adapted to readily turn. At the center of the furnace body is a toothed rim 23 which is engaged by the pinion 24 of a suitable motor 25 for revolving the furnace body. The furnace body is adapted to be lifted from the supporting frame as by means of a suitable crane 26 and carried to the balling furnace and its contents discharged into the balling furnace, after which the body of the boiling furnace is then restored to its initial operative condition on the supporting frame.

55 In practice the boiling furnaces are arranged at opposite sides of balling furnaces, and at a suitable distance therefrom. To enable the bodies of the boiling furnaces to be lifted and carried by the cranes they are provided with suitable rings 28 and also with bridles 27 to hold them steady when in operation. Said bridles are connected to beams 27^a which are suspended from the cranes.

55 It will be observed that the longitudinal

bars 27^a secured directly over each of the boiling furnaces 2, being carried by the chains 27 in such a manner that when, by means of the cranes these bars are shifted in one direction one of said chains will be pushed forwardly carrying the rotatable boiler along with it, thereby enabling the neck 18 of the boiler being slid off the neck 3^a of the stationary heater chamber, while the neck 19 is free to move into the flue 17, the opening 17^a in this flue being of a size large enough to permit the boiler being set at an upward inclination relatively to the flue so as to clear the neck 3^a as being removed out of the opening 17^a as the crane is being operated. By causing the crane to push the chains at the opposite end of the rotatable boiler the bar 27^a is moved so as to permit this boiler being properly positioned to permit its neck 18 being fitted over the neck 3^a, ready for another operation.

In the operation of our improved wrought iron making plant and in carrying out our improved process we in practice employ a crew of six men of whom two are ballers or puddlers, two are helpers and two are melters. One puddler and one helper are stationed at each side of the double balling furnace and one melter is stationed at each boiling furnace. Assuming that the furnaces are heated to the proper degree No. 1 boiling furnace will be charged "with a heat of metal" and at an hour subsequently No. 2 boiling furnace will also be charged "with a heat of metal." Immediately after each boiling furnace is charged it will be started in rotation. The revolving of the furnace body greatly facilitates the melting of the pig iron and during the course of about fifty minutes the pig iron is thoroughly melted and is ready for fluxing. This is done by throwing cinder or scale through a small door 31 in the larger door 20 of the boiling furnace and this action, in connection with the heat from the fire chamber and the revolving of the chamber body causes the metal to boil and this boiling is continued for about 20 minutes and the whole mass in the boiling furnace No. 1 is converted into grains of iron. The body of said furnace is then moved by the crane rearwardly toward the flue, to disengage the furnace mouth from the mouth of the fire chamber and said boiling furnace No. 1 is then swung by the crane to the balling furnace and its heat is transferred through the chute 14 and the door 13 to one side of the balling furnace of said chamber. This heat of raw or half finished iron is then mixed by the puddlers and their helpers and dropped, turned, broken up as it stiffens and when thoroughly prepared in this manner is then made into "balls", the balls being then taken to the squeezers, formed into blooms and then rolled into muck bar or pure wrought

iron. This manual operation requires from thirty to forty minutes. No. 1 boiling furnace having been discharged is immediately returned to its frame, recharged and the 5 same operation repeated therein. By the time that the heat from the boiling furnace No. 1 has been puddled and the balls taken from the balling furnace by the men on one side of the latter the heat of the boiling 10 chamber No. 2 is then ready and at the graining stage and immediately after the balls have been taken from the balling chamber by the men on one side thereof the charge from the boiling furnace No. 2 is placed in 15 the balling chamber of the balling furnace and the puddler and helper on the other side of such chamber employed. Hence the two boiling furnaces and the double balling furnace may be kept in continuous operation 20 and yet the workmen employed are not required to work so laboriously, although since they are only needed in the finishing periods of the process the output of wrought iron is very greatly increased.

25 By employing three crews for the furnaces on eight hour shifts the furnaces can be kept continuously in operation and a great economy of fuel effected.

It is becoming increasingly more and more 30 difficult to employ puddlers as the work is so laborious, under the usual process so as to discourage young men from learning the trade and the result is that serviceable wrought iron is much less than the demand 35 therefore and hence steel is largely employed in the arts instead of wrought iron when the latter would be preferred if it could be obtained.

By means of our improved process in 40 which the initial treatment of iron is mechanically performed and the employment of puddlers is only made necessary during the finishing stages the cost of making wrought iron is greatly reduced, and since 45 our process does not require such physical exertion on the part of the puddlers as was

formerly required more of the men are willing to work at the trade under the new conditions brought about by our process.

Having thus described our invention, we 50 claim:

1. In a device of the kind described, in combination a stationary heating chamber, a stationary flue spaced therefrom, a horizontally-disposed cylindrical boiling furnace, roller supports for said boiling furnace arranged therebeneath, said boiling furnace being provided at opposite ends with integral necks, said flue having an opening larger than one of said necks to allow the 60 latter to project centrally therein, an integral neck projecting from the heating chamber around which the opposite neck fits, said boiling furnace being of such a length that when said first neck is advanced in said opening the opposite neck is disengaged from the neck of said heating chamber, a cylindrical rack bar carried by said boiling furnace, and gear mechanism beneath said furnace adapted to rotate said rack and permitting the latter to slide beyond the former. 70

2. In a device of the kind described, in combination a stationary heating chamber, a stationary flue, a cylindrical boiling furnace disposed between said chamber and said flue, 75 said furnace being removably rotatably supported, and said furnace adapted to be longitudinally shifted to be positioned for removal from the support, a longitudinal bar extending over said furnace, a pair of chains 80 at the end of said furnace, secured to said bar and also to said furnace whereby said bar may swing longitudinally in either direction and cause one of said chains to push said furnace. 85

In testimony whereof we affix our signatures in presence of two witnesses.

PATRICK F. CHARLES.
JOHN J. BRODERICK.
